UNITED STATES PATENT OFFICE.

FRANKLIN W. HAGAR, OF NASHVILLE, TENNESSEE; ALBERT S. DAVIS EXECUTOR OF
FRANK W. HAGAR, DECEASED.

CARBURETER.

1,235,464.

Specification of Letters Patent. Patented July 31, 1917.

Application filed July 14, 1915. Serial No. 39,866.

To all whom it may concern:

Be it known that I, FRANKLIN W. HAGAR, a citizen of the United States, residing at Nashville, in the county of Davidson and 5 State of Tennessee, have invented new and useful Improvements in Carbureters, of which the following is a specification.

This invention relates to a carbureter for operation with either gasolene or coaloil, 10 and one object of the invention is to provide a carbureter comprising an organization of elements which automatically operate to give the proper proportionate parts of air and hydrocarbon throughout the same as an 15 entirety with the slightest possible amount of variation. A further object of the invention is to give an absolute mixture of air and hydrocarbon by completely breaking up or comminuting the globules of hydrocarbon 20 by mechanical means without additional heat. Practice has demonstrated that it is just as easy to vaporize low grade gasolene, coaloil, kerosene, etc., if properly handled, as it is to vaporize the more volatile hydro- 25 carbons. Heretofore it has been considered necessary to adopt a high temperature to vaporize low grade gasolene, kerosene, etc., but experiment has demonstrated that this 30 operation is not solely due to temperature, but on the contrary the sudden changes in temperature that the hydrocarbon is subjected to will effect a vaporization thereof. Therefore, it will be understood that the 35 present invention contemplates the provision of means for thoroughly breaking up or comminuting hydrocarbon globules by bringing the primary air into immediate contact with the hydrocarbon on its way to the motor and thereby lower the tempera- 40 ture of the hydrocarbon by volatilization below the temperature of the primary air. Another essential structural feature of the 45 present improved carbureter is that the float feed chamber, oil channels and air ducts are formed in a one-piece or integral casting. When the improved carbureter is once ad- 50 justed it remains so in all conditions of operations, and the adjustments can be made irrespective of the position of the vehicle containing the motor to which the carbureter is attached and will meet all road conditions perfectly.

One practical embodiment of the improved carbureter is illustrated in the accompanying drawings for the purpose of demonstrating an operative organization of elements carrying out the operation of mechanically breaking up the globules of the hydrocarbon used therewith and to illustrate the adjustment which accommodates all road conditions.

In the drawings:

Figure 1 is a rear elevation of the improved carbureter embodying the features of the invention.

Fig. 2 is a transverse vertical section through the carbureter.

Fig. 3 is a section taken in the plane of the line 3-3, Fig. 2.

Fig. 4 is a horizontal section taken in the plane of the line 4-4, Fig. 3.

Figs. 5 and 6 are sectional elevations, partially in diagram, showing the float feed regulation under different conditions.

Fig. 7 is a detail perspective view of a 75 rocker arm controlled by the float and engaging a portion of the needle valve which regulates the supply of hydrocarbon to the carbureter.

The numeral 5 designates a casing which in the main is formed as one casting and embodies a float chamber 6, an elongated nozzle chamber 7, an upper duct and mixing chamber extension 8 at one side, and a top cylindrical air charging duct 9 having an outlet 10. The float chamber 6 is provided with a removable closing cap 11, and the upper portion of the chamber 7 is reduced as at 12, the reduction being provided by increasing the thickness of the upper portion of the wall of said chamber, as at 13. The lower portion of the thickened wall 13 is interiorly screw-threaded, as at 14, to receive the upper screw-threaded head 15 of an elongated nozzle plug 16 having a bore 17 extending centrally therethrough from the lower end to a point near the upper terminal of the head 15 where a reduced bore 18 communicates therewith and continues through a reduced extremity 19 of the head 15, said extremity constituting a nozzle. The head 15 is also circumferentially channeled, as at 20, and communicating with this channel is an upwardly inclined duct 21.

for a purpose which will be presently explained. The lower end of the nozzle plug 16 is enlarged, as at 22, and formed with a flange 23 which closely abuts against the lower end of the wall of the nozzle chamber 7, and the bore 17 is closed at its lower portion by a screw plug 24 which may be removed as desired to clean the said bore 17. The lower portion of the chamber 7 has communication with the float chamber 6 by means of a port 25 formed in the intermediate wall 26 between the float chamber and the said nozzle chamber 7, and the bore 17 has communication with the nozzle chamber 7 through the medium of a port 27 formed in the nozzle plug, the said port 27, as shown by Fig. 2, extending fully across the plug. The upper portion of the bore 17 also has communication with the annular channel 20 through the medium of a cross-port 28 formed in the head 15 of the plug 16. The float chamber comprises an inward extension 29 from which depends an inlet member 30 having a lower exteriorly screw-threaded terminal 31 with a bore 32 extending therethrough and provided with a valve seat 33 for the lower end of a needle valve 34 vertically movable in the extension 29 and having its upper portion engaging a cap 35 with a bore 36, said cap being removably mounted in an upper tubular extremity 37 of the extension 29. The needle valve 34 is provided with a lower reduced end, as usual, to engage the seat 33, and at a point above the center thereof an elongated weight collar 38 is secured thereto or forms a part thereof and operates to normally close the valve or cause the latter to gravitate so that the lower reduced end will firmly engage the seat 33. The screw-threaded terminal 31 may have any suitable form of supply device, such as a pipe, connected thereto and whereby the gasolene, coaloil, kerosene or any other hydrocarbon of a like character may be fed to the float chamber 6.

In the float chamber 6 a float 39 is eccentrically mounted, and the particular mounting consists of a bushing 40 disposed therein, as clearly shown by Fig. 4, and through the bushing a rod or pin 41 is inserted and has bearing at its opposite ends in an enlargement 42 in the wall 26 and in the closing cap 11 of the float chamber. This pin constitutes the fulcrum of the float and is held against rotation, the bushing or sleeve 40 being free to rotate on this fulcrum pin. By means of the eccentric mounting of the float it will be seen that it will have a tilting or dipping action when the charge in the float chamber lowers below a certain point, and the control of the supply of the gasolene, kerosene or other hydrocarbon to the float chamber is accomplished through the needle valve 34 and the float 39 by means of

an intermediate rocker arm 43. The rocker arm 43 is fulcrumed on a pin 44 which passes through the outer extremity thereof, said extremity being in the form of a head 45 embodying two curved arms 46 which loosely engage the lower end of the weight collar 38 of the needle valve 34, the arms 46 embracing the valve stem, as clearly shown by dotted lines in Fig. 4. The inner end of the rocker arm 43 is enlarged and bifurcated, as at 47, and loosely engages a pin 48 projecting inwardly from the float 39 and carried solely by the latter. When the float tilts by reason of the lowering of the hydrocarbon in the chamber 6, the inner end of the rocker arm lowers therewith and the outer end of said arm elevates and raises the reduced extremity of the needle valve 34 from the seat 33 and permits the liquid hydrocarbon to flow into the chamber until the normal or predetermined level desired is obtained in the float chamber, when the inner extremity of the rocker arm elevates and the outer extremity or head 45 thereof lowers and permits the valve 34 to close the bore or inlet port or duct 32 to thereby shut off the further ingress of the hydrocarbon into the float chamber. To assist the float 39 in its sensitive operation it is provided with a weight, as at 49, said weight insuring a quick drop or lowering of the portion of the float 39 beyond the fulcrum point thereof. It will be seen that the float is of a tilting character, yet very compact in its organization, occupying a comparatively small space, and by this means the general proportions and dimensions of the carbureter are reduced, with advantages in the installation thereof without deterioration in operation. The operation of the float is clearly shown by Figs. 5 and 6, and as illustrated by Fig. 5 the float 39 has lowered in its chamber 6 by reason of the fall of the liquid hydrocarbon below a certain predetermined point, and it will be seen that the rocker arm 43 has been lowered at its inner extremity and its outer or head extremity elevated, and as a consequence the valve 34 is elevated. In Fig. 6 the liquid hydrocarbon in the chamber has been restored to its normal predetermined level and the float 39 has risen, and as a consequence the rocker arm 43 is in a reverse position and the valve 34 is closed.

The extension 8 is formed with a vertical duct 50 for the inlet of the primary air to what may be termed a preliminary carbureting chamber 51 having an enlarged portion 52 into which the duct 50 directly opens, and a lower reduced portion 53 intersecting the upper enlarged portion 52 as a continuation of the latter, a contracted throat 54 being formed at the point of intersection of the two portions 52 and 53. The chamber 51 as

a whole extends inwardly at a downward angle of inclination, and the lower reduced portion 53 thereof opens into the upper portion of the nozzle chamber 7. A screw plug 55 is fitted in and closes the upper terminal of the chamber 51 and has an inward extension or guide 56, the plug and extension being centrally bored to receive a valve stem 57 formed with an upper screw-threaded enlargement 58 to adjustably engage the adjacent portion of the plug 55 and an exterior head 59 whereby the stem 57 as a whole may be adjusted inwardly and outwardly as may be desired in accordance with the operation 10 of the carbureter. On the inner end of the stem 57 within the chamber 51 a valve 60 is secured and is movable downwardly into and upwardly from the throat 54 at the point of intersection of the upper enlarged portion 52 and the lower reduced portion 53 of the said chamber 51. The duct 50 is of materially less diameter than any part of the chamber 51 and the valve 60 is operable to modify the throat 54 relatively to 15 the said duct 50 in a manner which will be presently explained. The extension 8 also has a reduced vertical bore 61 formed therein and provided with a lower enlargement 62 opening through the bottom of the extension and provided with a closing screw plug or screw 63. The bore 61 with its enlargement 62 forms a secondary nozzle which opens into the upper enlarged portion 52 of the chamber 51, as clearly shown 20 by Fig. 2. The enlarged portion 62 of the nozzle is intersected by the duct 21 so that hydrocarbon may be fed in part through the nozzle plug 16 by way of the duct 21 to the nozzle opening into the chamber 51 as 25 explained.

Depending into the upper portion of the nozzle chamber 7 is a tube 64 which has its lower end extending over the nozzle 19 projecting upwardly from the head 15, the upper end of the tube opening into an annular chamber 65 in the cylindrical air charging duct 9 and provided by an inner reduced terminal or tubular extension 66 of a valve casing 67 which engages the inner wall of 30 the said air charging duct or chamber 9 and the outlet 10. The valve casing 67 is removably fitted in the air charging duct or chamber 9 and the latter is enlarged, as at 35 68, to form with the inner reduced portion 55 or tube 66 of the said valve casing the annular space or chamber 65. The inner reduced portion or tube 66 of the valve casing 67 is also formed with a plurality of openings 69 which establish communication between 40 the interior of the valve casing and the said annular chamber 65. The valve casing 67 has a flared inlet 70 with a spider or bracing means 71 formed with a central hub 72 having a screw-threaded bore therethrough to 45 receive the screw-threaded stem 73 of a valve 74 co-operating with a seat 75 at the inner terminal of the inlet 70. The valve 74 has an inwardly projecting sleeve 76 through which the stem 73 extends, and on the inner end of the stem is a disk or stop 77. Between the disk or stop 77 and the inner side of the valve 74 and surrounding the sleeve 76 and the inner portion of the stem 73 is a spring 78 which operates to maintain the valve 74 in closed condition, the valve stem 73 having a smooth surface for a greater portion of its length; or in other words the said stem is screw-threaded only to such extent as to render the stem practical in its adjustment in the hub 72. The outlet 10 is 50 provided with the usual butterfly or analogous valve 79 having an exteriorly projecting operating stem 80 and controlling the flow of the fuel or of the explosive mixture from the carbureter to the motor. 55

From the foregoing description it will be seen that the chamber 51 and the upper portion of the nozzle chamber 7 constitute a preliminary carbureting chamber and the tube 64 around the nozzle 19 induces an inward and upward flow of the mixture to the annular space or chamber 65; and from the latter the hydrocarbon and air in a comminuted or mechanically vaporized condition 60 pass through the openings 69 into the inner reduced extremity or tube 66 of the valve casing 67 where the mixture is charged with air and then passes on through the outlet 10, when the valve 79 is opened. 65

Assuming that the float chamber 6 is 70 charged with oil, either low grade or other gasolene or coaloil, to the level desired or predetermined, the valve 60 will be moved inwardly by adjusting the stem 57 until the shoulder 59 of the head 59 bears against 75 the outer end of the plug 55. By such adjustment the area of the throat 54 is reduced by the valve 60 to the area of the duct 50, and by this means the chamber 51 or the primary air charging means remains undisturbed or is filled with free air which is 80 open to co-operation with the nozzle in the extension 8 formed by the bore 61 in communication with the nozzle chamber 7 through the medium of the duct 21 by way 85 of the nozzle. The valve 74 is then operated to set up a suction or to draw up a charge of oil from the spray nozzle 19. This is a low speed adjustment only and is accomplished solely through the operation of the air valve 74 through the medium of the stem 73. The motor will then be speeded up until the charge becomes thin from lack 90 of oil, and then the valve 60 is adjusted outwardly to fully open the chamber 51, which 95 also serves as a duct. By moving the valve 60 outwardly to the position shown by Fig. 2, the restricted passage in the throat 54 is 100

eliminated and the inflowing air forms a partial vacuum at the point where the nozzle 61 communicates with the chamber or duct 51. The valve 60 is moved outwardly only a sufficient distance to throw up the desired amount of oil through the nozzle 61 by way of the duct 21, channel 20 and bore 17 of the nozzle plug 16. If all of the resistance to a free passage of air at the throat 54 was removed, or if at first the valve 60 was adjusted outwardly too far, the charge would be entirely too rich. Therefore it will be understood that this adjustment of the valve 60 in an outward direction should only be made at high speed of the motor so that when the motor dropped to low speed the vacuum would so weaken at the spray nozzle 61 that the oil would cease to flow through said nozzle and the spray nozzle 19 then be permitted to supply the oil for low speed. It will be observed that the adjustments regulating the mixtures are pneumatic and are only two in number. The purpose of these adjustments and the arrangement of the ducts and nozzles is to give a correct proportion of air and oil and absolutely mix the latter. The primary air enters through the duct 50 and thence passes to the spray nozzles 61 and 19 and breaks up the particles of oil and carries it in a seemingly vaporized or pulverized state into the annular chamber 65, where it is discharged through the openings 69 into the inner extension or tube 66 of the valve casing 67 and comes into contact with the main volume of air admitted by opening the valve 74. It will be understood that the number of openings 69 should be sufficient to cause a thorough mixture of the oil and air. By adjusting the valve 60 inwardly or outwardly a proper mixture can be determined, and if the shoulder 59^a of the head 59 is against the outer end of the plug 55 there is no vacuum at the spray nozzle 61 for the reason that the valve 60 will then be projected inwardly within the throat 54 and the latter consequently restricted in its area. If the valve is moved outwardly to give a full opening or to clear the throat 54, the vacuum at the spray nozzle 61 will be equal to that at the spray nozzle 19 for the reason that the restricted passage in the air duct as a whole will then be established by the duct 50. The object of the float feed organization, as will be understood, is to maintain a constant level of oil at a fixed elevation in the spray nozzles 61 and 19. As hereinbefore indicated, the float 39 when in normal position has the greater portion thereof submerged, and the up and down movements of the float controlled by the level of the oil in the chamber 6 sets up a corresponding movement of the needle valve 34. The point of contact of the pin 48 on

the rocker arm 43 is about the center of gravity in every direction relatively to the float in view of the position of the weight 49. If the pin 48 was omitted and the float allowed to move freely as in ordinary float constructions embodied in the usual forms of carbureters, two oil levels would be established which would be objectionable, especially in the operation of the present improved carbureter. By using the bushing 40 in the float 39 on the fulcrum pin 41 and positioning the said fulcrum eccentrically, the float is caused to have a partial rotation during its upward and downward movements without relieving any of its weight or operating effect from the pin 48. The effect of the weight 49 on the float is essential in the operation of the latter. When the liquid hydrocarbon of whatever character it may be begins to lower from the predetermined normal elevation thereof in the float chamber 6, the weighted float partially rotates and starts downwardly or gravitates in the said chamber, and as the greater portion of the float carrying the weight lowers it naturally becomes heavier, as it were, or more effective in its leverage on the pin 48 and the gravitating needle valve 34 is more quickly opened by reason of the correspondingly quick downward movement of the float, and the float chamber will therefore rapidly fill to a sufficient extent to start the float on its upward movement. As the float rises the resistance of the weight 49 becomes less by being overcome by the buoyancy of the float, and as a consequence the float in its upward movement is quickened or is rendered faster than the elevation of the oil surface and the valve 34 is caused to close more rapidly than it would otherwise, and the result is that the predetermined oil level within the chamber 6 is soon reestablished and maintained throughout all conditions without any perceptible change. In other words, the particular mounting and construction of the float 39 encourage the float to rapidly descend when the liquid hydrocarbon in the float chamber 6 begins to lower and said float becomes submerged and is not delayed by the downward gradual movement of the liquid, the valve 34 being opened to permit ingress of a charge of liquid hydrocarbon to the chamber 6 before the normal level of the liquid in the float chamber has been materially modified. Conversely, the float begins to rise and reaches an elevation sufficient to shut off the valve 34 or permit the latter valve to fully gravitate just at the time that the normal level of liquid hydrocarbon is reached in the float chamber. It will therefore be seen that the upward and downward movements of the float are more rapid than the corresponding movements of the liquid hydro-

carbon in the chamber 6, the acceleration of the downward movement of the float being due to the weight applied thereto and the quickening of the upward movement of said 5 float resulting from a greater buoyancy existing in view of the particular mounting of the float and the less effective action of the weight under the latter conditions. There is no resistance to the up and down movements of the float by the fulcrum of the latter or the pin 48, and as a consequence the float will be very sensitive in its operation in maintaining a predetermined level of the hydrocarbon in the float chamber 6 and will 10 not be affected by movements over uneven road surfaces, and hence when the carbureter is once adjusted it remains so in all 15 conditions of operation. As hereinbefore indicated, the adjustments can be made irrespective of the position of the vehicle embodying the motor to which the carbureter is attached, and the carbureter will regularly operate to supply the motor with a proper mixture without deterioration, no 20 matter what the road conditions may be.

It will also be observed from the foregoing that the liquid hydrocarbon, such as gasolene, low grade gasolene, kerosene or other suitable hydrocarbon, will be mechanically broken up or comminuted by contact with the air at the nozzles, as hereinbefore described, and a partial mixture will ensue prior to the subjection of the sprayed or comminuted hydrocarbon to the main 30 volume of air in the inner extension or tube 35 66 of the valve casing 67, the richness of the mixture depending solely upon the adjustments hereinbefore described. One of the main advantages of the improved carbureter is the economical use of the hydrocarbon in forming the explosive mixture without relying upon heat as a vaporizing medium.

What is claimed is:

45 1. A carbureter having a nozzle chamber closed at the bottom and provided with an oil supply in communication with the lower portion thereof, a main nozzle dividing the said chamber into distinct upper and lower parts, the said nozzle being tubular and in communication with the lower part of the said chamber and having a reduced extremity projecting into the upper part of the chamber, the carbureter also having air 50 inlet means laterally communicating with the upper separate part of the said chamber and a secondary spray nozzle opening into the air inlet means at a distance from the point of communication of the latter with the upper part of the chamber, adjusting means in the air inlet means for regulating the mixture of air and hydrocarbon, and means in communication with the nozzle chamber for supplying a main volume of

air to the primarily associated air and hydrocarbon to effect a mechanical breaking up and comminution of the globules of the hydrocarbon and form an absolute mixture of air and hydrocarbon prior to exit from the carbureter. 65

2. A carbureter having a nozzle chamber in communication with an oil supply and provided with a closed bottom, a main nozzle extending upwardly through the said chamber and dividing the latter into upper 70 and lower separate parts, the carbureter also having air inlet means communicating with the nozzle chamber and a secondary spray nozzle exposed to the air inlet means at a distance from the point of communication of the latter with the nozzle chamber, and means in communication with the nozzle chamber for supplying a main 75 volume of air to the primarily associated air and hydrocarbon to effect a mechanical breaking up and comminution of the globules of the hydrocarbon to form an absolute mixture of air and hydrocarbon prior to exit from the carbureter. 80

3. A carbureter having a nozzle chamber 90 with a main nozzle extending upwardly therethrough and separating the chamber into upper and lower parts, the chamber and nozzle having communication with the hydrocarbon supply, an air inlet open to the 95 upper part of the chamber and upper terminal of the said nozzle, a secondary spray nozzle opening into the said air inlet at a distance from the point of communication of the latter with the nozzle chamber, and means in communication with the upper part of the chamber and the main nozzle 100 for supplying a main volume of air to the primarily associated air and hydrocarbon to effect a mechanical breaking up and comminution of the globules of the hydrocarbon to form an absolute mixture of air and hydrocarbon prior to exit from the carbureter. 105

4. A carbureter having an air inlet, main 110 and secondary nozzles respectively in communication with opposite extremities of the said air inlet and also provided with means for supplying them with hydrocarbon, adjusting means in the said air inlet between the nozzles, means for supplying the main volume of air into the carbureter independently of the said air inlet, and communicating means between the means for supplying the main volume of air and the 115 said air inlet whereby air and hydrocarbon may be primarily associated in proportionate parts and fed to the main volume of air at a lower temperature than the latter air. 120

5. A carbureter having dual spray nozzles 125 therein separated from each other, a primary air feeding means to the opposite extremities of which both nozzles are opera-

tively exposed, means for supplying the nozzles with hydrocarbon and to set up a spraying action thereof and whereby hydrocarbon and air may be preliminarily associated in proportionate parts, and means for supplying the main volume of air to the carbureter, the preliminarily associated air and hydrocarbon being passed to the main volume of air at a less temperature than the latter air to effect a thorough breaking

up of the hydrocarbon and commingling of the latter with the main volume of air within the carbureter.

In testimony whereof I have hereunto set my hand in presence of two subscribing witnesses.

FRANKLIN W. HAGAR.
